UNITED STATES PATENT OFFICE.

CHARLES F. GOLDTHWAITE, OF DULUTH, MINNESOTA, ASSIGNOR TO KLEARFLAX LINEN RUG COMPANY, A CORPORATION OF MINNESOTA.

RUG CORNER.

Application filed October 18, 1921. Serial No. 503,546.

To all whom it may concern:

Be it known that I, CHARLES F. GOLDTHWAITE, a citizen of the United States, and resident of Duluth, in the county of St.

5 Louis and State of Minnesota, have invented certain new and useful Improvements in Rug Corners, of which the following is a specification.

This invention relates to rug corner to be 10 attached to the under side of rugs to prevent same from curling, or slipping on the floor and comprises improvements upon devices of this general character heretofore known, for the purpose of more effectively 15 carrying out the desired objects.

According to this invention I provide a corner preferably made of rubber or similar material, as heretofore, which is of characteristically varying thickness in all directions from or a slight distance from the right angled corner. The portion at this corner is made the thickest for the purpose of bringing the maximum weight at the corner and the material tapers therefrom in all 20 directions toward the acute angles. Along the median line normal to the hypotenuse, the taper commences at the corner or slightly inward therefrom and is at first gradual and then changes so as to more rapidly approach to the thinnest edge at the middle portion of the hypotenuse, the ends of the hypotenuse being thicker than the middle but not as thick as at the right angle. By this construction, the upper surface of 25 the rug will lay smooth on a floor, without having abrupt ridges due to the thickness of the underlying rug corner, as in devices heretofore proposed with which I am familiar, and the rug also clings more closely to 30 the floor. By reason of having the thickness at the acute angles greater than at the middle portion of the hypotenuse, the rug corner will snap back more easily into position when raised from the floor, owing to the 35 extra stiffness imparted to the edges. Moreover, this provides sufficient thickness at the corners to enable the thread or other attaching means to hold more securely.

In the accompanying drawing showing a 40 preferred embodiment of the invention,

Figure 1 is a perspective view of a portion of a floor and a rug provided with the invention,

Figure 2 is a plan view of one form,

Figure 3 is an elevation of the hypotenuse side,

Figure 4 is a section on line 4—4 of Figure 2,

Figure 5 is a section on the line 5—5 of Figure 2, and

Figure 6 shows a modification.

The device is of general right triangular shape corresponding to the corner of a rug with one surface substantially plane, and the other surface, generally the bottom or 60 the one next the floor is smooth but of varying surface as above indicated. In Figure 2, 1 represents the right angle apex, and 2, 2, the acute angled corners each having sewing or other attaching holes 3. As seen in Figures 4 and 5, the body is thickest at apex 1 and tapers substantially uniform therefrom or nearly therefrom to corners 2. In Figure 3, the hypotenuse edge is represented in elevation by 4, and as will be seen is thickest at corners 2 and thinnest at the middle portion 5. Along the median line 6 commencing at the apex 1, the taper to abut the portion 7 is relatively slight as compared with the taper from 7 to edge 5 as seen in Figure 4, these differing tapers all merging into each other without abrupt angles or changes in surface.

The result of such construction is that the weight is concentrated at the apex 1, tending to hold the device down; the outside edges between apex 1 and corners 2 gradually taper but yet have considerable resilience, while the hypotenuse edge tapers from the corners 2 to the thinnest portion at 5, giving the whole device a characteristic resilience which causes it to immediately resume its natural flat shape when bent. At the same time, there is good contact with the floor, so that sliding or slipping is prevented. Also, the apex 1 and corners 2 are of sufficient thickness to properly hold the securing threads, which are of insufficient size to affect the operation of the device.

In Figure 6 a similar principle is carried out, but adapted for somewhat larger rugs where the corners 8 corresponding to corners 2, are considerably extended so as practically to constitute wings 9, the edges of which taper from the corners 8 to the inner corners 10 similar to Fig. 5, while there is a slight additional taper to the inner corners 11 from the corners 10, the por-

tion 12 between the inner corners 10 being of about the thickness of portion 5 in Figure 3. From the edge 12 the thickness increases relatively rapidly to the portion 13 corresponding to 7 and thence more gradually to or nearly to the apex 1. This form is more specially adapted for very large rugs where the amount of material in the device should be cut down without affecting the operation of the device as a whole.

In either form, the portion at the apex 1 may be flat for a slight distance, say one inch on each side, before the taper 6 commences.

15 A device of this character has several advantages over previous devices in holding more securely without being apparent because of objectionable thickness on the top of the rug, thereby obviating worn places 20 on the rug due to the angles of the corner and also because of the resilience causing the whole device to snap back on the floor when partially elevated. The device will be made in various sizes according to the requirements, the one herein shown in Figure 2 being of approximately eight inch hypotenuse and the portion 7 being about one and one half inches inside, which proportions I have found to give satisfactory results. It 30 is further to be understood that the bottom or floor face of the device can carry attaching directions, trade mark and other indicia, and be roughened or corrugated to increase the resistance to slipping.

35 In the accompanying claims, the term apex refers to the portion underlying the rug corner, the base is the side opposite the apex, or hypotenuse in a right triangle, and the corners are the points underlying the 40 edges of the rug at opposite ends of the base, these definitions applying to either form, although the base in Figure 6 is not a straight line as in Figure 2.

What I claim is:

1. A rug corner of flexible material having a thickened apex portion and of tapering reduced thickness toward the base. 45
2. A rug corner of flexible material having a thickened apex portion and of tapering reduced thickness toward the base, the 50 taper along the median portion being varying.
3. A rug corner of flexible material having a thickened apex portion and of tapering reduced thickness toward the base, the 55 taper along the median portion being varying, and along the edges being uniform.
4. A rug corner of flexible material having a thickened apex portion and of tapering reduced thickness toward the base, the 60 thickness along the base being less at the middle than at the respective corners.
5. A rug corner having its apex thickest, the corners of less thickness, and the median portion of the base of least thickness, the 65 several cross sections tapering between portions of different thickness.
6. A rug corner of flexible resilient material having its apex thickest, the corners of less thickness, and the median portion 70 of the base of least thickness, the several cross sections tapering between portions of different thickness.
7. A rug corner of flexible resilient material having its apex thickest, the median 75 portion of the base of least thickness and having its sides extended beyond the median portion of the base to extended corners, the thickness of said corners being intermediate between the thickness of said median portion of the base and the apex. 80

Signed at Duluth, in the county of St. Louis and State of Minnesota this 10th day of October A. D. 1921.

CHARLES F. GOLDTHWAITE.
